WINDOW CONSTRUCTION

Thomas W. Holt and John F. Levan, Elkhart, Ind., assignors, by mesne assignments, to The Syracuse Trust Company, Syracuse, N. Y., a corporation of New York, trustee

Application January 9, 1931, Serial No. 507,670

1 Claim. (Cl. 16—220)

This invention relates to window constructions, such as are used in railway cars, motor busses etc., and has for its object, a particularly simple and efficient means for securing a detachable window stop to the window frame or post structure, and also a particularly simple and efficient means for holding the sash from rattling and weather tight.

10 The invention consists in the novel features and in the combinations and constructions hereinafter set forth and claimed.

In describing this invention, reference is had to the accompanying drawings in which like characters designate corresponding parts in all the 15 views.

Figure 1 is a fragmentary elevation, partly broken away, of a window structure embodying my invention.

20 Figure 2 is a vertical sectional view taken substantially centrally of Figure 1, looking to the right.

Figure 3 is an enlarged sectional view taken on line 3—3, Figure 1.

25 Figure 4 is a fragmentary edge view of the sash, the contiguous parts of the window frame being also shown.

Figure 5 is a fragmentary edge view of one of the uprights of the window frame or post structure.

30 Figure 6 is an enlarged fragmentary sectional view taken on the plane of line 6—6, Figure 1.

Figure 7 is a sectional view on line 7—7, Figure 6.

35 Figure 8 is a sectional view on line 8—8, Figure 6.

1 designates the side members or post structure of a window frame, this being provided with outer and inner stops 2, 3 forming a guide for the sash 4, there being a guide for each edge of the sash.

40 The post structure is formed up of sheet metal and is here shown as rectangular in general form in cross section open at its outer side, and is set with its open outer side toward the wall of the window opening 5. It is secured in the window opening in any suitable manner as by screws passing through holes 1^a therein into the wall of the window opening.

45 The outer stop 2 consists of a flange reversely folded from a flange 6 of the post structure 1 and extending beyond the inner wall of the post 1 to lap the sash 4 and form an outer stop therefor. This outer stop 2 is also shaped to receive a holder 7 for a weather strip 8 which engages flatwise against the outer face of

be of any suitable material, as felt or material formed with a nap or bristles.

The inner stop 3 is detachable and is formed up from sheet metal in the general form of a U-shaped channel. The wall of the channel adjacent the sash abuts edgewise against the post 1 and is provided at intervals with tongues 9 which enter slots 10 formed in the body 1, the tongues 9 and slots 10 serving to locate the stop 3. The outer side of the detachable stop 3 is provided with an extension 3^a which laps the upright end wall of the body 1. The tongues are provided on plates 9^a which are secured as by spot welding at 9^b to the detachable stop 3.

15 The detachable stop 3 is secured to the post structure by means which detachably interlock with the body 1, and this means consists of one or more plungers, as a plunger 11 movable through openings in the bottom of the channel of the stop 3, the plunger having a button or cross bar 12 at 20 its inner end, and a head 13 at its outer end. The cross bar moves through a slot 14 in the body 1, upon inward movement of the plunger, and into interlocking engagement with the walls thereof upon a partial rotary movement, or quarter turn 25 of the plunger. This locking feature per se forms no part of this invention, but the mounting of the plunger to be presently described is one of the principal features of this invention.

30 The plunger is mounted in a tubular guide 15 surrounding the plunger and extending into the channel of the detachable stop, the guide having an inturned shoulder 16 at its inner end through which the plunger slides, and having its outer end extending through an opening 17 in the bottom 35 of the channel formation of the detachable stop, and secured to said bottom by an upsetting or riveting operation.

A compression spring 18 encircles the plunger and thrusts at its inner end against the shoulder 40 16, and at its outer end against the head 13. Obviously, inward movement of the plunger will cause the cross head 12 thereof to pass through the slot 14, and a partial rotary movement of the plunger will interlock the cross head with the 45 body 1 of the post structure, and the spring will hold the cross head 12 snugly engaged with the post structure. To remove the stop for the purpose of removing the sash, the reverse of this operation takes place, and the plunger is given 50 a quarter turn to align its cross head 12 with the slot 14 so that the spring is free to react and withdraw the cross head through the slot 14. Any desired number of plungers and associated parts may be used.

The sash is provided with a sash holder at each lower corner thereof. These sash holders may be of any suitable form, size and construction. They usually include a housing 19 mounted 5 on the outer side of the bottom lower rail of the sash, a pinch handle or lever 20 pivoted to the housing, and operating motion transmitting means in the housing, or in the bottom rail of the sash to transfer the movement of the lever 10 to a locking bolt 21, this locking bolt being preferably located within the sash and movable through the edge thereof.

In the illustrated embodiment of our invention, the locking bolt 21 extends through openings 22 in the wall of the post structure, that is, the wall opposed to the edge of the sash, and means is provided within the post structure for coacting with the bolt to press the bolt and hence, the sash outwardly against the outer stop to hold 20 it from rattling, and also to hold it tightly closed so that it is weather tight when the sash is closed.

As here illustrated, the bolt 21 is provided with a beveled edge 21a which coacts with means as blocks 23 located within the hollow post structure 1 and secured thereto as by fastening members 24, these blocks having beveled faces 25 arranged to coact with the beveled faces 21a of the bolt 21.

As the sash holders are located at the extreme 30 lower edge of the sash, means is also provided for pressing the upper portion of the sash against the outer stop when the sash is entirely closed, this means being carried by the detachable inner 35 stop 3. This means as here shown comprises compression devices as spring pressed shoes 26 located in each detachable stop 3 and movable through slots 27 therein into engagement with the stiles of the sash. These spring pressed 40 shoes 26 are here shown as elongated and provided with eyes 28 at their upper and lower ends through which extend guide rods 29 extending forwardly and rearwardly between the front and rear walls of the channel of the outer stop, and springs encircling said rods and thrusting against 45 the ends of the shoe 26.

In the window here illustrated, there is a stationary upper sash 30, the bottom rail of which coacts with or laps the top rail 31 of the sash 4, 50 and these rails are provided with coacting weather tight or weather strip means 32 on their abut-

ting faces. This weather strip means may be of any suitable form, size and construction.

The upper rail 33 of the stationary sash 30 is formed up of sheet metal and comprises a flange 34 for lapping the inner face of the top wall of the window opening, this flange 34 being secured to the wall of the window opening, as by screws 35. The top rail 33 is shown as formed up of two sheet metal parts to provide a hollow body having a reentrant glass receiving groove 36, these two parts having lapping flanges, or flanges lying one on the other which form the flange 34 of the top rail. The flange 34 extends laterally or tangentially from the hollow body of the rail 33. 15

When the sash is closed, the sash holders owing to the wedging action of the bolts and the action of the compression devices 26 press the sash against the outer stop holding it weather tight, and also against rattling. The compression device 26 also presses the top rail of the movable sash against the lower rail of the stationary sash 30 rendering the joint between the same weather tight when the sash is closed. 20

Owing to the particular means for holding the 25 stop in position, the stop is firmly and rigidly secured against reaction of the sash due to the wedging action of the sash holders and of the compression devices 26 and at the same time, is readily detachable and replaced when desired. 30

What we claim is:

The combination of a window frame including a demountable window stop, in the form of a channel and arranged with its open side toward the adjacent frame member, means within the 35 channel of the stop and carried thereby for securing the stop in position, comprising a tubular guide fixed to the bottom of the channel of the stop and projecting toward the open side of the 40 stop, a holding member slidably axially of the 45 guide and operable to interlock with the frame through a slot therein upon successive axial and partial turning movements, the holding member having a head for fitting in the outer end of the tubular guide and exposed on the outer side of the bottom of the channel and a spring interposed between the head and the inner end of the tubular guide and acting to thrust the holding member outward.

THOMAS W. HOLT.
JOHN F. LEVAN.
